Ira D. Nickerson
ATTORNEY.

UNITED STATES PATENT OFFICE.

MATTHEW O'FARRELL, OF DETROIT, MICHIGAN, ASSIGNOR TO CHICAGO PNEUMATIC TOOL COMPANY, OF NEW YORK, N. Y., A CORPORATION OF NEW JERSEY.

FLUID-PRESSURE HAMMER.

Application filed July 27, 1926. Serial No. 125,153.

This invention relates to percussive tools operated by fluid pressure. It concerns the valve and piston action of such tools generally with particular reference to that type 5 which utilizes a piston with an interior chamber into which extends a motive fluid inlet plug.

Among the objects of the invention are to provide a simple compact form of percussive 10 tool which is fast and powerful, to effect exact coordination of piston and valve movement, to increase the force of the blow in tools of the specific type described, and in general to improve prior devices in the interests of 15 more efficient and satisfactory service.

In order to illustrate the invention one concrete embodiment thereof is shown in the accompanying drawings, in which:

Fig. 1 is a longitudinal vertical sectional view of a hammer embodying the invention; and

Fig. 2 is a sectional view similar to Fig. 1 showing the parts in a different position.

The embodiment of the invention chosen 25 for the purpose of illustration comprises a pneumatic hammer having a cylinder 3 providing a piston chamber 4 in which reciprocates a hammer piston 5 arranged to impart blows to a working tool such as a drill steel 30 6, supported in a front head 7, either directly or through an anvil block 8 mounted in a guide member 9 between cylinder 3 and front head 7. Piston 5 is hollowed out rearwardly as indicated to provide an interior chamber 35 5^a with a reduced opening 5^b. A plug member 10 mounted in the cylinder so as to project centrally and axially into piston chamber 4 cooperates with opening 5^b in the piston and serves as an inlet member for motive 40 fluid to the chamber 5^a by reason of an axial bore 11 through plug 10 which communicates with the motive fluid inlet passage 12, which is a branch of supply passage 13 in back head 14 of the drill, which supply passage may be controlled by the manually operated throttle valve 15. Another branch supply passage 16 leads from the supply 13 to an automatic valve 17 of the spool type having end heads 17^a and 17^b of equal diameter and recipro- 45 cal in valve chamber 18. End head 17^a controls passage 19 opening into the rear end of piston chamber 4 which is enlarged for a short distance by an annular groove 20. End head 17^b controls passage 21 opening through

a port 21^a in the front end of the piston 55 chamber 4.

A passage 22 leads from enlarged end 20 of piston chamber 4 to the pressure area presented by end head 17^b, and a live air passage 23 of smaller size extends from supply passage 13 to the pressure area presented by opposite end head 17^a. A vent passage 23^a extends from passage 23 and opens into piston chamber 4 so as to be under control of piston 5. In certain positions of the piston this 65 vent passage registers with a groove 24 in the exterior of the piston. Cylinder 3 has main exhaust ports 25 and 26 for the piston chamber under control of piston 5.

The cycle of the operation of the hammer 70 is as follows: Assuming throttle valve 15 to be opened as indicated and starting with the parts in the position shown in Fig. 1, motive fluid from supply 13 passes through the bore 11 of plug 10 continuously into chamber 5^a 75 and is operative against the forwardly directed pressure area 5^c provided by the end wall of this chamber. Since the reduced bore 5^b of the piston registers with the reduced neck 10^a of plug 10, motive fluid from chamber 5^a passes into the enlarged chamber 20 80 at the rear end of piston chamber 4 and is operable against the other forwardly directed area 5^d provided by the rear end of the piston for a limited period or until the piston has moved forwardly to a slight extent. Meantime the motive fluid passing to chamber 20 is effective through passage 22 against end head 17^b of valve 17 to move it to the 85 position shown so as to admit motive fluid from branch 16 around the central reduced portion of the valve also to the rear end of the piston chamber through passage 19. The forward end of the piston chamber is open to exhaust through port 25. As the piston moves forward to strike its blow the valve exhaust passage 23^a no longer communicates with the groove 24 but is sealed by the piston so that motive fluid entering through the live air passage 23 builds up against end head 17^a 90 and becomes effective as soon as the rear end of the piston chamber is open to exhaust through uncovering of vent 26 by the piston. Valve 17 then shifts to the position shown in Fig. 2 cutting off passage 19 and establishing communication between passages 16 and 21 whereupon motive fluid enters the front 95 of the piston chamber through port 21^a to be 100 105

effective against return area 5^a of the piston to drive the piston on its rearward stroke against the constant pressure of forwardly directed area 5^a. As the piston approaches the rear of the piston chamber it establishes communication between vent passage 23^a of the valve and main exhaust port 26 through its groove 24 but valve 17 does not move rearwardly until the piston reaches the point where motive fluid from constant pressure chamber 5^a passes around neck 10^a of plug 10 into the rear end of the piston chamber to augment the pressure of the air trapped therein and is effective through passage 22 to shift the valve. This completes the cycle.

From the above it will be apparent that the present invention relates to a fluid pressure hammer having a piston with two forwardly directing pressure areas and one return area, that one forward area is continuously subjected to pressure while the second forwardly directed area is intermittently subjected to pressure for a limited period, that a valve is arranged also to admit motive fluid to this second forwardly directed area from an independent source and to continue the admission after the piston controlled means is closed, that the valve is thrown to admitting position by the motive fluid admitted by the piston control means, that the valve also controls the motive fluid supply to the return area of the piston, that the forward continuously active pressure area of the piston is provided by an interior chamber to which motive fluid is continuously admitted by a necked plug inlet, and that the hammer comprises few parts of substantial size which may be cheaply manufactured and assembled.

40 While a preferred form of the invention has been herein shown and described, it is to be understood that the invention is not limited to the specific details thereof but covers all changes, modifications, and adaptations within the scope of the appended claims.

I claim as my invention:

1. A fluid pressure tool comprising a cylinder providing a piston chamber, a piston reciprocable therein having two pressure areas for driving it in one direction and a single area for returning it, means subjecting one of said first named areas continuously to motive fluid, piston controlled means for admitting motive fluid to the second of said first named areas at the beginning of the stroke of the piston in one direction, and a valve controlling a second motive fluid supply to said second of said first named areas and the motive fluid supply to said return area.

2. A fluid pressure tool comprising a cylinder providing a piston chamber, a piston reciprocable therein having two pressure areas for driving it in one direction and a single area for returning it, means subjecting

one of said first named areas continuously to motive fluid, piston controlled means for admitting motive fluid to the second of said first named areas at the beginning of the stroke of the piston in one direction, and a valve controlling a second motive fluid supply to said second of said first named areas and the motive fluid supply to said return area, said valve being moved in one direction by the motive fluid admitted to the second of said first named areas by said piston controlled means.

3. A fluid pressure tool comprising a cylinder providing a piston chamber, a piston reciprocable therein having two pressure areas for driving it in one direction and a single area for returning it, means subjecting one of said first named areas continuously to motive fluid, piston controlled areas for admitting motive fluid to the second of said first named areas at the beginning of the stroke of the piston in one direction, and a valve controlling a second motive fluid supply to said second of said first named areas and the motive fluid supply to said return area, said valve being movable to the position to admit motive fluid to the second of said first named areas by the motive fluid admitted thereto by said piston controlled means and being movable to the position to admit motive fluid to the return area of said piston by a built-up pressure controlled by said piston.

4. A fluid pressure tool comprising a cylinder, a hammer piston reciprocable therein, said piston having a chamber therein providing a pressure area for driving it forwardly, a fixed member extending axially into said cylinder to admit motive fluid continuously to said chamber, said member having a reduced portion to permit motive fluid from said chamber to pass for a limited period to the rear end of said piston to be effective against the area there presented, and an automatic valve controlled by said piston for admitting motive fluid to said last named area of the piston during and after said limited period, said valve being thrown to admit motive fluid to said area by the motive fluid admitted thereto by said member and said piston.

5. A fluid pressure tool comprising a cylinder, a hammer piston reciprocable therein having opposed pressure areas at its ends and an interior pressure area, a plug member fixedly mounted in said cylinder and extending within said piston continuously to supply motive fluid to said interior area, means permitting passage of motive fluid from the interior of said piston to one end area, and an automatic valve controlled by said piston for controlling the admission of motive fluid to both said end areas.

6. A fluid pressure tool comprising a cylinder, a hammer piston reciprocable therein,

having opposed pressure areas at its ends and an interior pressure area, a plug member fixedly mounted in said cylinder and extending within said piston continuously to supply motive fluid to said interior area, cooperating means on said piston and said member permitting access of motive fluid from the interior of said piston for a limited period to one end area of the piston, and an automatic valve controlling a separate motive fluid supply to both said end areas of the piston.

7. A fluid pressure tool comprising a cylinder, a hammer piston reciprocable therein, having opposed pressure areas at its ends and an interior pressure area, a plug member fixedly mounted in said cylinder and extending within said piston continuously to supply motive fluid to said interior area, said member having its exterior reduced at one point to permit motive fluid to pass from the interior of the piston to one end area thereof in one position of the piston, and an automatic valve controlling a separate motive fluid supply to both said end areas of the piston.

8. A fluid pressure tool comprising a cylinder, a hammer piston reciprocable therein, having opposed pressure areas at its ends and an interior pressure area, a plug fixedly mounted in said cylinder and extending within said piston continuously to supply motive fluid to said interior area, cooperating means on said piston and said member permitting access of motive fluid from the interior of said piston for a limited period to one end area of the piston, and an automatic valve controlling a separate motive fluid supply to both said end areas of the piston, said valve being moved in one direction on admission of motive fluid from the interior of the piston to said end area.

9. A fluid pressure tool comprising a cylinder, a hammer piston reciprocable therein, having opposed pressure areas at its ends and

an interior pressure area, a plug member fixedly mounted in said cylinder and extending within said piston continuously to supply motive fluid to said interior area, cooperating means on said piston and said member permitting access of motive fluid from the interior of said piston for a limited period to one end area of the piston, and an automatic valve controlling a separate motive fluid supply to both said end areas of the piston, said valve being moved on admission of motive fluid from the interior of the piston to said end area to a position to admit additional motive fluid from said separate supply to said same area.

10. A fluid pressure tool comprising a cylinder, a hammer piston reciprocable therein, said piston having a chamber therein providing a pressure area for driving it forwardly, a fixed member extending axially into said cylinder to admit motive fluid continuously to said chamber, said chamber having a reduced portion to permit motive fluid from said chamber to pass for a limited period to the rear end of said piston to be effective against the area there presented, a spool valve having end heads of equal diameter operating in timed relation with the movements of the piston, said valve having a central reduced portion continuously supplied with motive fluid and said end heads controlling the distribution of the motive fluid to the opposed end areas of the piston in alternation, and means whereby the valve is moved to the position to admit motive fluid to the forwardly directed end area of the piston so as to supplement the limited admission of motive fluid thereto from said piston chamber.

Signed by me at Detroit, Mich., this 19th day of July, 1926.

MATTHEW O'FARRELL.
